Primary Examiner — Prabhakar Deshmukh*(74) Attorney, Agent, or Firm* — Dunlap Bennett & Ludwig PLLC(57) **CLAIM**

The ornamental design for an electronic audio device, as shown and described.

DESCRIPTION

FIG. 1 is a front perspective view of the electronic audio device.

FIG. 2 is a front elevation view of the electronic audio device.

FIG. 3 is a rear elevation view of the electronic audio device.

FIG. 4 is a right side elevation view of the electronic audio device.

FIG. 5 is left side elevation view of the electronic audio device.

FIG. 6 is a top plan view of the electronic audio device; and, FIG. 7 is a bottom plan view of the electronic audio device. The broken lines shown in the drawings illustrate portions of the electronic audio device that form no part of the claimed design.
